UNITED STATES PATENT OFFICE

102,421

DESIGN FOR A MARBLE GAME DEVICE

George A. Fry, Saginaw, Mich.

Application November 2, 1936, Serial No. 65,644

Term of patent 7 years

To all whom it may concern:

Be it known that I, George A. Fry, a citizen of the United States and resident of Saginaw, in the county of Saginaw and State of Michigan, have invented a new, original, and ornamental Design for a Marble Game Device, of which the following is a specification, reference being had to the accompanying drawing, forming a part thereof.

In the drawing, Fig. 1 is an elevation in perspective of a marble game device showing my new design, and Fig. 2 is a bottom end view thereof.

I claim:

The ornamental design for a marble game device, substantially as shown.

GEORGE A. FRY.
